DESIGN FOR A KITCHEN CABINET

John Richard Harris, Broadview, Ill., assignor to Sears, Roebuck and Co., Chicago, Ill., a corporation of New York

Application May 8, 1942, Serial No. 106,818

Term of patent 7 years

To all whom it may concern:

Be it known that I, John Richard Harris, a citizen of the United States of America, residing at Broadview, in the county of Cook and State of Illinois, have invented a new, original, and ornamental Design for a Kitchen Cabinet, of which the following is a specification, reference being had to the accompanying drawing, forming a part thereof.

The drawing shows a perspective view of a kitchen cabinet, embodying my new design.

I claim:

The ornamental design for a kitchen cabinet, substantially as shown.

JOHN RICHARD HARRIS.
